UNITED STATES PATENT OFFICE.

HERMAN GOLDSMITH, OF NEW YORK, N. Y.

COMBINED CONTAINER AND HUMIDOR.

Application filed August 11, 1922. Serial No. 581,085.

To all whom it may concern:

Be it known that I, HERMAN GOLDSMITH, a citizen of the United States, and resident of New York city, in the county of New York and State of New York, have invented certain new and useful Improvements in Combined Containers and Humidors, of which the following is a specification.

My invention relates to a combined container and humidor and more particularly to a container for packaging cigars or the like adapted to be employed as a humidor during vending and periodic consumption of the cigars; and has special reference to the provision of containers or cans of the type now used for packaging cigars modified by simple changes to be rendered serviceable as a humidor during the period of sale or use of the cigars.

As is well known, one of the common methods of packaging and selling cigars or the like consists in the employment of a cylindrical container or can provided with a bottom having a plurality of so-called "breathing" perforations intended to permit a circulation of humidified air through the can to keep the cigars therein in a moistened and good condition. These cigar cans are designed and constructed with the intent that the cigar dealer keep or store the cigar filled cans in a moist atmosphere so as to provide for humidified air circulating through the breathing perforations. In selling these cigars to the consuming public the cans should ordinarily be kept within the dealer's show or display case so as to have the cigars continuously subjected to the action of the humidor forming part of the display case. In practice, however, the dealers

have been inclined to place and have formed the habit of keeping an opened cigar can on the top of the display case and on the counter, thus removing the cigars from the humidified influence and subjecting them to the atmosphere. This practice results in causing rapid deterioration and drying of the cigars, rendering them undesirably brittle and unsaleable. To avoid this objection and to permit the selling of the cigars directly "from-the-counter" while subjecting the cigars to the proper humidifying atmosphere is a prime desideratum of my present invention.

The principal objects of my present invention may be said to include, besides the provision of a container capable of performing

the service above referred to, the provision of a container of the type or kind now employed in commerce in which the top cover is made to interchangeably fit the top and bottom of the can body and is provided with an absorbent substance which, when the cover is removed from the can top and fitted onto the can bottom during sale or gradual consumption of the cigars, is moistened or saturated with water so that the air circulating through the perforated bottom will be moistened or humidified; the further provision of a container and humidor constructed to permit the fitting or mounting of the cover on the can bottom with the absorbent substance spaced from the perforated bottom so as to provide an air chamber therebetween and the still further provision of a container and humidor of this nature in which the ordinary and presently employed can is utilized and modified in a simple and inexpensive manner to permit of the efficient performance of the new uses referred to.

To the accomplishment of the foregoing and such other objects as may hereinafter appear, my invention consists in the elements and their relation one to the other, as hereinafter particularly described and sought to be defined in the claims, reference being had to the accompanying drawings which show a preferred embodiment of my invention and in which:

Figure 1 is an elevational view of the container and humidor with part broken away,

Figure 2 is a cross sectional view thereof showing the container when used as a humidor,

Figure 3 is a reduced view showing the bottom of the container, and

Figure 4 is a view of a detail.

Referring now more in detail to the drawings, for packaging the cigars I provide a container or can which comprises a receptacle having the cylindrical body side wall 10 usually made of sheet metal provided at the top end with the marginal bead 11 and at the lower end with a bottom 12 provided with a plurality of spaced so-called "breathing" perforations 12', the said bottom being preferably inset and comprising a marginal flanged element secured to the body side wall 10 as by interlocking with the inturned marginal lip 13 thereof. The receptacle or can body is provided with the

flanged cover 14 normally closing the top of the same and constructed to interchangeably fit the top and bottom of the same, the can body 10 being likewise constructed to permit of the cover being fitted to its bottom, as shown in Fig. 2 of the drawings, during selling and consuming use of the cigars.

As heretofore mentioned, the dealer or store-keeper, in the prior practise, after opening a can, places the same and cigars therein on the counter, the cigar can being thus subjected to the influence of ordinary atmospheric conditions until the quantity of cigars packaged in the can is sold to the trade. As mentioned, the cigars during sale when removed from the proper humidifying atmosphere, rapidly dry and become objectionable and unsaleable. For the purpose of obviating this objection I provide the top cover 14 with an absorbent substance which may be moistened after the same is removed from the can body and which, when the cover is mounted on the bottom of the can body, acts as a humidifying medium for moistening the air circulating through the breathing perforations of the perforated bottom. More specifically, I take one or more sheets 15 of blotting paper and insert the same in the top cover 14, the sheets being carried by the cover and held in position in the cover in any desired way, as for example by cutting the sheets so as to frictionally fit the flange of the cover. If desired the cover may be provided with an outwardly turned bead such as 14^a in Fig. 4 for suitably receiving the sheets. With this construction the sheets of absorbent material normally lie between the inturned bead 11 of the can body and the top wall of the cover 14 and when the said cover is removed from the top and mounted on the bottom of the can body the sheets of blotting paper when moistened or saturated with water will humidify the air circulating through the perforated bottom 12.

For the purpose of providing a construction in which the absorbent sheets 15 are

suitably spaced from the perforated bottom 12 I provide means whereby the cover 14 may be so positioned on the bottom of the can body so as to produce an air chamber 16 between the perforated bottom and the humidifying material. To this end, in addition to providing an inset bottom 12, the can body 10 may also be provided with a marginal bead 17 adjacent the bottom end of the side wall 10 and so positioned as to form a stop means cooperating with the flange of the cover 14 to position or locate the cover in the manner shown in Figure 2 of the drawings, with an air chamber 16 between the perforated bottom and the blotter sheet or sheets 15.

The manner of making and using my container and humidor will be fully apparent from the above detailed description thereof. It will be further apparent that with the provision of the absorbent sheets 15 carried by the top cover 14 that the dealer will be enabled to continue to display the cigars on the counter and sell the same with economy and convenience without causing the rapid deterioration and drying of the cigars, the saturating with water of the blotting sheets 15 producing a self-contained humidor unit.

While I have shown my device in the preferred form, it will be obvious that many changes and modifications may be made in the structure disclosed without departing from the spirit of the invention, defined in the following claim.

I claim:

A container for tobacco products, including a body and a slip-on flanged cover, and a sheet or pad of blotting paper held within the flange against the body of the cover, said sheet being of an area to fit within the flange to prevent displacement thereof, the flange of the cover having an internal bead to hold the sheet in place.

Signed at New York city, in the county of New York and State of New York this 24 day of July, A. D. 1922.

HERMAN GOLDSMITH.
